UNITED STATES PATENT OFFICE

THOMAS J. MATASSA, OF LOS ANGELES, CALIFORNIA

DESIGN FOR A PASTRY CRUST

Application filed June 22, 1932. Serial No. 44,164. Term of patent 14 years.

To all whom it may concern:

Be it known that I, THOMAS J. MATASSA, a citizen of the United States, residing at Los Angeles, in the county of Los Angeles and State of California, have invented a new, original, and ornamental Design for a Pastry Crust, of which the following is a specification, and wherein the pastry crust is pan-like in formation provided with an inclined side wall curved outwardly and downwardly at its upper edge, the side wall and the curved upper wall being transversely fluted or corrugated in form, reference being had to the

accompanying drawing, forming part thereof.

Figure 1 is a plan view of the design for a pastry crust, and,

Figure 2 is a side elevation.

I claim:

The ornamental design for a pastry crust, as shown and described.

Signed at Los Angeles, in the county of Los Angeles, State of California, this 6th day of June, 1932.

THOMAS J. MATASSA.
